KNIFE OR THE LIKE

Clayton A. Laughlin, Minneapolis, Minn., assignor to Arthur Salm Inc., Chicago, Ill., a corporation of Illinois

Filed Aug. 13, 1959, Ser. No. 57,178

Claims priority, application Austria Apr. 9, 1959

Term of patent 14 years

(Cl. D22—3)

Fig. 1 is a perspective view of a knife showing my new design;

Fig. 2 is a side elevational view of the knife shown in Fig. 1;

Fig. 3 is a bottom edge view thereof;

Fig. 4 is a top edge view thereof;

Fig. 5 is an enlarged sectional view taken on the line 5—5 of Fig. 2; and

Fig. 6 is an enlarged butt end view.

The dominant features of the design lie in the portions shown in full lines on the drawing.

I claim:

The ornamental design for a knife or the like, substantially as shown and described.
